DESIGN FOR A COLLAPSIBLE MUSIC STAND

Willie Berg, Chicago, Ill.

Application May 13, 1942, Serial No. 106,885

Term of patent 14 years

To all whom it may concern:

Be it known that I, Willie Berg, a citizen of the United States, residing in the city of Chicago, county of Cook, State of Illinois, have invented a new, original, and ornamental Design for a Collapsible Music Stand, of which the following is a specification, reference being had to the accompanying drawing, forming a part thereof, in which:

Fig. 1 is a front perspective view of a collapsible music stand, showing my design;

Fig. 2 is a rear perspective view; and

Fig. 3 is a side perspective view thereof, in its collapsed position.

I claim:

The ornamental design for a collapsible music stand, as shown.

WILLIE BERG.
